RADIO RECEIVER CIRCUIT ARRANGEMENT

Jan van der Heem, The Hague, Netherlands, assignor to Hartford National Bank and Trust Company, Hartford, Conn., as trustee

Application January 20, 1943, Serial No. 473,026
In the Netherlands January 29, 1941Section 1, Public Law 690, August 8, 1946
Patent expires January 29, 1961

4 Claims. (Cl. 250—20)

1

This invention relates to a radio-receiving set in which the electrode system used for detection together with an amplifying electrode system is arranged about a common cathode in one vacuum tube. Such combined electron discharge tubes are often used in modern radio-receiving technique. Thus, for instance, low frequency output amplifying tubes incorporating a diode are commonly known.

The use of the said combined tubes in circuit arrangements in which the negative grid voltage for the amplifying part and the retarding voltage for automatic volume control are obtained by means of a resistance in the cathode-lead brings about certain difficulties when the direct voltage produced upon detection in the detector circuit, is used as a control voltage for automatic volume control of the high- or intermediate-frequency amplifying tube preceding the diode. Difficulties also arise if the low-frequency signal produced upon detection in the detector circuit is not directly supplied to the control grid of the amplifying electrode system which has its cathode in common with the detector, but is first amplified in another tube. In the usual circuits, wherein the cathode leads of the various tubes are connected each individually to the negative or earth lead of the set, these difficulties consist in that in the first-mentioned case an undesirable relaxation oscillation is produced and in the second case self-oscillation of the low-frequency amplifying system occurs.

According to the invention these difficulties are overcome by connecting the cathode lead of the high-frequency or intermediate frequency tube preceding the detector and the cathode lead of the succeeding amplifying tube which amplifying tube may be interposed if required, between the detector and the amplifying tube combined therewith, directly to the cathode of the detector tube.

The invention will be more fully explained by reference to the accompanying drawing representing the diagram of one embodiment of the invention, from which the parts which do not appear to be of any material pertinence to the invention have been omitted. The embodiment concerns a superheterodyne receiver, but it will be appreciated that the invention is not limited to receiving sets of this type and that it also applies to any other receiver type.

Through the intermediate-frequency transformer 1, 2 the intermediate-frequency voltages are supplied to the control grid of the intermediate-frequency amplifying tube 4. The amplified signals appearing in the anode circuit of

2

this tube are supplied through the intermediate-frequency transformer 9, 10 to the detector diode 50 of the duo-diode-pentode 17. The low-frequency alternating voltage set up across the resistance 13 is entirely or partly supplied through the condenser 14 to the amplifying grid 51 of the cathode-ray indicator tube 19 which is constructed in such manner that the control grid 51 of the voltage amplifying part is electrically insulated from the control grid 52 of the indicator part. The low-frequency alternating voltage set up at the amplifying anode 53 of the tube 19 and evolved across the anode resistance 26 is supplied through the condenser 18 and the leakage resistance 20 to the control grid 54 of the tube 17. The anode circuit of the tube 17 comprises the output transformer 24, 25.

The use of the circuit referred to above involves a few difficulties which the invention purports to avoid.

The cathode lead 55 of tube 17 includes resistances 27, 28 which are bridged by the condenser 29. The negative voltage for the control grid 54 of tube 17 is taken from the junction of resistances 27 and 28. The voltage across the resistances 27 and 28 is the retarding (delay) voltage for automatic volume control; to such end the automatic volume control voltage is produced across resistance 39 by the second diode 56 incorporated in tube 17 and fed through the condenser 16. The voltage so derived is supplied through the resistance 31 which is by-passed by condenser 32, to the tubes to be controlled.

It is found that a relaxation phenomenon appears when the direct voltage produced by the detector diode 50 across the resistance 13, is supplied through the resistance 12 as a control voltage to the control grid of the intermediate-frequency amplifying tube 4 and when the cathode of the tube 4 is connected to the earth lead either directly or in the usual way through the resistance 7 for obtaining the negative grid voltage. In fact, the alternating voltage still available across the combination of resistances 27 and 28 and condenser 29 is then supplied through the resistance 12 to the control grid of the tube 4 and will modulate the intermediate-frequency signal, which gives rise to the said relaxation phenomenon. This effect is particularly pronounced at low sound frequencies.

According to the invention this phenomenon can be avoided by connecting the cathode 51 of tube 4 (through the resistance 7, if available) and the cathode side 58 of the control grid circuit of tube 4 to the cathode of tube 17 in order to

prevent the low-frequency voltage from the cathode circuit of tube 17 from reaching the control grid of tube 4. In this case the cathode side of the circuit 2, 3 is connected through the condenser 5 and the lead 59 to the cathode of tube 17. The condenser 6 serves for by-passing of the negative grid bias voltage developed across the resistance 7, and the condenser 8 serves to by-pass the screen-grid voltage of tube 4.

Another difficulty arises when interposing a low-frequency amplifying tube, for instance in form of the amplifying part of tube 19 in the embodiment referred to above, between the detector diode 50 and the amplifying part of tube 17. If the cathode 60 of such an amplifying tube is connected to the earth lead (through a resistance for the negative grid bias voltage; for example through a resistance 23 by-passed by the condenser 22) the low-frequency alternating voltage developed across the combination 27, 28, 29 will be supplied in the correct phase for obtaining damping reduction to the control grid 51 of the amplifying tube (amplifying part of tube 19), so that the low-frequency amplifying part of the set breaks into oscillation.

According to the invention this can be avoided by connecting the cathode of the amplifying tube (through the resistance for obtaining the negative grid bias voltage) also to the cathode 55 of the detector diode. This is shown in the drawing wherein the cathode 60 of tube 19 is connected to the cathode 55 by means of a conductor 61.

What I claim is:

1. A radio receiver circuit arrangement comprising an electron-discharge tube having a control grid, three anodes and a cathode common to the control grid and the anodes to provide signal detection diode elements, automatic volume control diode elements and amplifier elements, a detector load resistance coupled to the said signal detection diode elements, a volume control load resistance coupled to the anode of the automatic volume control diode elements and to earth, a cathode resistance interconnecting the said cathode and earth and providing a negative grid voltage for the said control grid and a retarding voltage for automatic volume control, and an amplifier tube having a control grid coupled to the detector load resistance and a cathode connected to the junction of said cathode resistance and the said common cathode.

2. A radio receiver circuit arrangement comprising an electron-discharge tube having a control grid, three anodes and a cathode common to the control grid and the anodes to provide signal detection diode elements, automatic volume control diode elements and amplifier elements, a detector load resistance coupled to the said signal detection diode elements, a volume control load resistance coupled to the automatic volume control diode elements and to earth, a cathode resistance interconnecting the said cathode and earth and providing a negative grid voltage for the said control grid and a retarding voltage for automatic volume control, and a radio-frequency amplifier tube having an anode coupled

to the said signal detection and volume control diode elements, a control grid coupled to the detector load resistance, and a cathode connected to the junction point of said cathode resistance and the said common cathode.

3. A radio receiver circuit arrangement comprising an electron-discharge tube having a control grid, three anodes and a cathode common to the control grid and the anodes to provide signal detection diode elements, automatic volume control diode elements and amplifier elements, a detector load resistance coupled to the said signal detection diode elements, a volume control load resistance coupled to the anode of the automatic volume control diode elements and to earth, a cathode resistance interconnecting the said cathode and earth and providing a negative grid voltage for the said control grid and a retarding voltage for automatic volume control, and an audio frequency amplifier tube having an anode coupled to the said control grid, a control grid coupled to the detector load resistance and a cathode connected to the junction point of said cathode resistance and the said common cathode.

4. A radio receiving circuit arrangement comprising an electron discharge tube having a control grid, three anodes and a cathode common to the control grid and the anodes to provide signal detection diode elements, automatic volume control diode elements and amplifier elements, a detector load resistance coupled to the said signal detection diode elements, a volume control load resistance coupled to the anode of the automatic volume control diode elements and to earth, a cathode resistance interconnecting the said cathode and earth and providing a negative grid voltage for said control grid and a retarding voltage for automatic volume control, a radio-frequency amplifier tube having an anode coupled to the anodes of the said signal detection and volume control diode elements, a control grid and a cathode, a resistance interconnecting the control grid of the radio frequency amplifier tube and a negative potential point of the detector load resistance, and an audio frequency amplifier tube having a control grid coupled to the detector load resistance, an anode coupled to the control grid of the first discharge tube and a cathode, the cathodes of said amplifier tubes being connected to the junction of the said cathode resistance and the said common cathode.
